UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

REFRIGERATOR-CAR-DOOR OPERATING AND LOCKING MEANS.

Application filed April 27, 1928. Serial No. 273,199.

This invention relates to improvements in refrigerator car door operating and locking means. Certain types of refrigerator cars, especially milk cars, are usually equipped with single doors made up of two hinged doors each, which when forced closed have a "toggle" action and are jammed tightly within the frame of the door opening. It will be appreciated that considerable force is required to close this type of door and also to break the "toggle" joint in opening the same. The main object of my invention is to provide simple and efficient operating means for doors of the type referred to, by which a powerful leverage may be exerted to force the same closed and also to break the "toggle" joint in opening the same. Another object of the invention is to provide an operating mechanism for refrigerator car doors composed of hinged sections, including rotary operating means co-operating with the door sections, either to break the sections at their hinged connection to force the door open or to straighten out said hinged connection to force the door tightly closed and jam it into the opening of the door frame. A more specific object of the invention is to provide operating means for a refrigerator car door hinged at one side on the door frame and composed of two sections which are hinged together, which when straightened out snugly fit the door opening, wherein the operating means comprises a swinging lever actuated mechanism, including rotary trunnion-like cam acting elements which are disposed angularly with respect to each other and turn in bearing members mounted on the door sections at opposite sides of the hinged connection between said sections.

Other and further objects of the invention will more clearly appear from the description and claims hereinafter following.

In the drawing, forming a part of this specification, Figure 1 is a side elevational view of a portion of a wall of a refrigerator car, showing the door and illustrating my improvements in connection therewith. Figure 2 is a horizontal, sectional view, corresponding substantially to the line 2-2 of Figure 1, this figure also showing the door

sections in dotted lines in partly open position. Figure 3 is a vertical, sectional view of the central portion of one of the door sections, showing the operating means in connection therewith corresponding substantially to the line 3-3 of Figure 1. And Figure 4 is a vertical sectional view, corresponding substantially to the line 4-4 of Figure 1.

In said drawings, 10 indicates the side wall of a refrigerator car provided with a door opening 11 to which the door member proper is hinged. The door proper is composed of sections 12 and 13, which are hinged together adjacent their inner edges by hinge members 14-14. Four hinge members 14 are shown in the present disclosure. The door proper comprising the hinged sections 12 and 13 is swingingly mounted on the door frame, being supported by hinge means 15. The hinge means 15 comprises two heavy sections extending for the height of the door and provided with a plurality of co-operating hinge ear members 16-16 which receive the usual hinge pin or bar.

The hinge member 15 is disposed on the inner side of the car wall, so that the entire door comprising the sections 12 and 13 will be swung inwardly of the car when opened, and folded against the inner side of the wall. The hinge members 14, as shown, are disposed on the outer side of the door sections 12 and 13, thus hinging these sections together to swing in a direction reverse to the swinging movement of the door.

In carrying out my invention, I provide the improved operating mechanism comprising, broadly, an operating lever member A having two trunnion members B-B and two bearing members C-C co-operating with the trunnions and mounted on the respective door sections 12 and 13.

The bearing members C-C are of the same design and each comprises a supporting bracket member 17 fixed to the corresponding door section adjacent the hinge connection thereof with the other door section. The supporting bracket is in the form of a U-shaped strap provided with top and bottom flange sections which are secured to the outer side of the door section by any suitable means, such as bolts 18-18. The central base plate 19 of disc-like form co-operates with each U-shaped bracket. The base plate

19 is seated in a pocket provided in the corresponding door section. The connecting section of the U-shaped bracket and the plate 19 are provided with aligned bearing openings 20-20. The top and bottom arms of the U-shaped bracket are cut away so as to present curved bearing surfaces as shown in Figures 1 and 4, and the connecting members also cut away interiorly at opposite sides 10 above and below the center to provide for the swiveling movement of the bearing member proper. The bearing member proper, which is indicated by 21, is in the form of a block having trunnion members 22-22 at the 15 front and rear sides thereof, which are swiveled in the openings 20. The rear wall of the bearing block 21 is flat and bears on the plate 19. The top and bottom wall sections of said bearing are substantially 20 straight, as indicated in Figure 1, and the front wall is curved as shown in Figures 3 and 4. As will be evident, the bearing 21 is thus mounted for vertical swinging movement to a limited extent in the bracket 17. 25 Each bearing member 21 is provided with a cylindrical bearing opening 23 which is disposed at an inclination to the corresponding door section, in the normal position of the parts, as clearly shown in Figure 2. 30 The operating lever A is in the form of an elongated bar having an operating handle grip 24 at the outer end thereof. At the opposite end, the lever member A is provided with trunnions B-B. As shown, the trunnion members B are so arranged that they project on opposite sides of the lever and engage with the corresponding bearing members C. In order to provide for movement 35 of the door sections 12 and 13, with respect to each other when the operating lever is moved, the trunnion members B are arranged angularly with respect to each other, as clearly shown in Figure 2.

Adjacent the handle end, the operating 45 lever A is enlarged, as indicated at 25, the enlarged section being provided with an opening 26. When the door is closed, the handle portion of the operating lever A may be sealed in the usual manner, a bracket 27 having an upstanding portion 28 which extends through the opening 26 of the lever A being employed for this purpose. The upstanding portion 28 is provided with the usual seal receiving opening 29, shown in 50 Figure 3, disposed outwardly of the lever A when in its vertical position, adapted to receive the car seal proper.

As shown, the door section 12 is provided with the usual packing means at the free 60 edge thereof, the edge of the door being rounded and co-operating with a rounded vertical pocket 30 on the corresponding door frame member.

The door section 12 is also provided with 65 a grab handle 31, whereby the same may be

positioned while the lever A is manipulated.

The operation of my improved door operating and locking means is as follows:

Assuming that the door is in the closed position illustrated in Figures 1 and 2, and 70 the door is opened by breaking the hinged connection between the two sections 12 and 13. In this connection, it is pointed out that the arrangement of the hinged connection produces a "toggle" effect in the closing of 75 the door, thereby jamming the door sections tightly into the door opening. In opening the door, the enormous force exerted by this "toggle" arrangement must be overcome. The operating lever A is swung upwardly 80 from the position shown in Figures 1 and 3, thereby turning the trunnions B in the bearing members C. Due to the angular arrangement of the trunnions, the door sections 12 and 13 will be forced to swing 85 relatively to each other during the swinging movement of the lever A, referred to. As will be evident during the first portion of the operation described, the lever A is pulled outwardly away from the door until 90 it reaches a substantially horizontal position, and is then swung toward the door until it assumes a substantially vertical position. As will be evident, the last portion 95 of the swinging movement of the lever being toward the door, the force exerted by the operator in manipulating the lever also aids in the swinging movement of the door proper on the hinged sections 15. When the operating lever A assumes the vertical 100 position referred to, the door sections 12 and 13 will be in the dotted line position shown in Figure 2 and are, as shown, drawn entirely clear of the pocket 30 of the door frame member. When the parts have assumed the dotted line position shown in Figure 2, the lever A as swung in a reverse direction away from the door and downwardly toward the door, while the door section 12 is held by the operator by gripping 110 the hand hold 31, thereby rotating the trunnion members B to the original position with respect to the door sections 12 and 13, bringing the latter into alignment. The door comprising the sections 12 and 13 is 115 then swung inwardly against the inner side of the wall of the car.

When it is desired to close the door, the same is swung from its position on the inner side of the wall to partly closed position. 120 The operating lever is then swung outwardly and upwardly and toward the door to swing the two sections 12 and 13, with respect to each other, while the door section 12 is held by the operator until they assume the angular position indicated by dotted lines in Figure 2. The door is then adjusted on the hinge 15 so as to assume approximately the dotted line position shown in Figure 2. The operating lever is then manipulated 125 to 130

straighten out the sections 12 and 15 and bring the same in alignment by swinging the lever downwardly away from the door and then inwardly toward the door, while at 5 the same time guiding the door section 12 by the hand hold 31. This movement of the lever will effect rotation of the trunnions B—B in such a manner as to bring the sections 12 and 13 of the door into alignment 10 and force the door tightly into the door opening, seating the edge of the section 12 in the pocket 30 of the frame member of the door opening. In forcing the door closed during the last part of the swinging 15 movement of the lever A, that is, when it is being forced toward the door, the edge of the door 12 will have entered the pocket 30 of the frame member and the door will thus be held against inward movement.

20 Inasmuch as the door section 13 is hinged at one edge and the remote portion of the door section 12 is in engagement with the pocket 30 of the door frame member, the door sections in the final closing movement 25 thereof will have a "toggle" action which tightly jams the door into the door opening, thus compressing the sealing material at the door edge.

While I have herein shown and described 30 what I consider the preferred manner of carrying out my invention, the same is merely illustrative and I contemplate all changes and modifications which come within the scope of the claims appended hereto.

35 I claim:

1. In an operating mechanism for a refrigerator car door hinged at one edge to a door frame and composed of two hinged sections, the combination with an operating lever 40 swingingly supported on said hinged sections and having means thereon for moving said sections relatively to each other, to align said sections when the lever is swung in one direction to force the door tightly closed, and to swing said sections out of alignment to 45 force the door open.

2. In a refrigerator car construction, the combination with a door frame member having a door opening; of a door hinged to 50 said frame for closing said opening, said door comprising two hinged sections; means for moving said door sections with respect to each other, said means including an operating member having connection with both 55 door sections, said operating member, when actuated in one direction, bringing said door sections in alignment when the door is partly closed, to jam said door into said door opening, and, when operated in the reverse 60 direction, swinging said door sections out of alignment to break the hinge joint and force the door partly open.

3. In an operating mechanism for a refrigerator car door hinged at one edge to a 65 door frame to swing in one direction to

opened position, said door comprising two sections hinged to be swung in a reverse direction to said swinging movement of the door, to move said sections out of alignment, the combination with an operating lever provided with actuating means at opposite sides thereof, anchored to the respective door sections to effect relative swinging movement of the door sections to bring said sections in alignment when the lever is swung 70 in one direction to force the door closed and to swing said sections out of alignment with each other to force said door partly open.

4. In an operating mechanism for a refrigerator car door hinged at one edge to the 80 door frame and composed of two hinged sections, the combination with an operating lever provided with angularly disposed actuating portions, separate bearing members on said door sections in which the said actuating portions engage, to swingingly support said lever, whereby when said lever is swung in one direction the sections of the door are brought into alignment to force the door closed and when said lever is swung in the 85 reverse direction the door sections are swung angularly to each other to force the door open.

5. In a refrigerator car provided with a door opening in the wall thereof and a door 90 member for closing said opening, the door member being hinged at one edge and composed of two hinged sections, the combination with a swinging operating lever movable away from and toward said door, said 95 operating lever having door actuating portions anchored to the respective door sections, said actuating portions swingingly supporting the lever on the door, said actuating portions swinging the door sections out 100 of alignment to force the door open when the operating lever is swung in one direction away from and then toward the door, and said actuating portions swinging the door 105 sections into aligned relation to force the 110 door closed when the operating lever is swung in a reverse direction away from and then toward the door.

6. In a refrigerator car provided with a door opening in the wall thereof and a door 115 member hinged at one edge for closing said door, the door being composed of two hinged sections, the combination with an operating lever having oppositely projecting trunnions at one end thereof; of a bearing support on 120 each door section, each co-operating with one of said trunnions, whereby when said lever is swung in one direction the door sections are brought into aligned relation to force the door closed, and when the lever is 125 swung in the reverse direction the door sections are swung out of alignment to force the door open.

7. In a refrigerator car provided with a door opening in the wall thereof and a door 130

member hinged at one edge for closing said opening, the door being composed of two hinged sections, the combination with an operating lever having oppositely projecting 5 trunnions at one end thereof, said trunnions being angularly disposed with respect to each other; of a bearing support on each door section, provided with a swiveled bearing member, each bearing member co-operating 10 with one of said trunnions, whereby when said lever is swung in one direction the door sections are brought into aligned relation to force the door closed and when swung in the reverse direction the door sections are 15 swung out of alignment to force the door open.

8. In a refrigerator car provided with a door opening in the wall thereof, and a door member hinged at one edge for closing said 20 opening, the door being composed of two hinged sections, the combination with an operating lever having projections at one end thereof, angularly disposed with reference to each other; of separate anchoring means 25 on each door section, disposed on opposite sides of the hinged connection of said sections for swingingly supporting said operating lever by said projections, said projections operating upon swinging movement of the 30 lever in one direction to swing the door sections angularly to each other to force the door open, and upon swinging movement of the

operating lever in the reverse direction to swing the door sections into aligned relation to force the door closed. 35

9. In an operating mechanism for a door composed of two hinged sections, the combination with a bearing member swiveled to each door section; of an operating lever provided with oppositely projecting trunnions 40 at one end thereof, said trunnions being angularly disposed with reference to each other and journaled in said bearing members respectively.

10. In an operating mechanism for a door composed of two sections hinged together at their adjacent edges, the combination with a bearing member swiveled to each section, said bearing members being disposed on opposite sides of the hinged connection between said door openings, each bearing member having a trunnion receiving portion disposed at an angle to the corresponding door section; of an operating member swingingly supported on said door, the operating member being provided with trunnion members at one end on opposite sides thereof, angularly disposed with respect to each other and journaled in said bearing members respectively. 50 55

In witness that I claim the foregoing I have hereunto subscribed my name this 25th day of April, 1928.

JOHN F. O'CONNOR.
